UNITED STATES PATENT OFFICE

SAUL RITTER, OF NEW YORK, N. Y.

DESIGN FOR A BRACELET CHAIN

Application filed October 24, 1931. Serial No. 41,518. Term of patent 7 years.

To all whom it may concern:

Be it known that I, SAUL RITTER, a citizen of the United States, residing in New York, in the county of New York and State of New York, have invented a new, original, and ornamental Design for Bracelet Chain, of which the following is a specification, reference being had to the accompanying drawings, forming part thereof.

Fig. 1 is a plan view of a section of connected links embodying the present ornamental design;

Fig. 2 is a side view of the links shown in Fig. 1 and

Fig. 3 is a perspective view of one of the links shown in Fig. 1 and having an end piece or connector attached thereto.

The figures in the drawings are shaded to show contrasting colors although it is contemplated to make the design of one color.

I claim:

The ornamental design for a bracelet chain as shown and described.

SAUL RITTER.
